UNITED STATES PATENT OFFICE.

LAMPERT BEMELMANS, OF NEW YORK, N. Y.

DESIGN FOR A BRACELET.

Application filed July 21, 1922. Serial No. 3,164. Term of patent 3½ years.

To all whom it may concern:

Be it known that I, LAMPERT BEMELMANS, a citizen of the United States, residing at 570 West 182nd Street, in the city, county, and State of New York, have invented a new, original, and ornamental Design for a Bracelet, of which the following is a specification, reference being had to the accompanying drawing, forming part thereof.

The drawing is a view of a bracelet showing my design.

I claim:

The ornamental design for a bracelet, as shown.

LAMPERT BEMELMANS.
